UNITED STATES PATENT OFFICE.

KARL GUSTAV MAGNUS RUNBÄCK, OF STOCKHOLM, SWEDEN.

MACHINE FOR BENDING METAL BARS AND THE LIKE.

1,385,278.

Specification of Letters Patent.

Patented July 19, 1921.

Application filed January 5, 1920. Serial No. 349,485.

To all whom it may concern:

Be it known that I, KARL GUSTAV MAGNUS RUNBÄCK, a subject of the King of Sweden, residing at Stockholm, in the Kingdom of Sweden, have invented a new and useful Improvement in Machines for Bending Metal Bars and the like, of which the following is a specification.

The present invention relates to a machine for bending metal bars, rods, and the like of the type which is provided with two stationary supports or stops for the bar and a third rotatable support or stop, preferably rotatable around one of the stationary supports, said third support obtaining from a driving device a periodical reciprocatory oscillatory movement with an interval or dwell after every period of the movement. The invention is principally characterized by this that for transmitting motion to the rotatable support, said support is connected with a rotatable disk around the periphery of which is placed a rope or the like which is connected to a rotary crank or the like driven by the driving device. The machine is suitably provided with an adjustment device so constructed that the length of the interval or dwell, or the length of the movement of the rotatable support may be regulated, and said adjustment device is preferably so arranged as to render possible a continuous adjustment, so that the adjustment is thus not limited to any particular positions of adjustment.

An embodiment of the invention is shown in the accompanying drawings. Figure 1 shows a side elevation of the machine. Fig. 2 shows a longitudinal section of the upper portion of the machine. Fig. 3 shows a plan view of the machine with the machine table removed. Fig. 4 shows a plan view of a portion of the machine table. Fig. 5 shows a detail view of one of the stationary supports, and Figs. 6 and 7 show two bars bent by means of the machine.

The machine frame 1 is provided with a table 2. A shaft 3 is journaled vertically in the machine frame and the upper end 4 of said shaft projects above the machine table. Said end 4 of the shaft forms one of the stationary supports or stops for the bar or rod to be bent. Below the machine table 2 a disk 5 is secured to the shaft 3, said disk carrying a stud 6 which projects through a curved slot 7 in the machine table. Said stud 6 forms the rotatable support or stop

for the bar or rod. The slot 7 in the machine table is covered by a disk or plate 8 provided with two holes and placed over the end 4 of the shaft and the stud 6. Outside the periphery of said disk 8 a third support or stop for the rod or bar is secured to the machine table. Said support consists of the block 9 secured to the machine table, and the slide 10 which is fitted into the block and carries the roller 11 against which the bar or rod is to bear. The position of the slide 10 and roller 11 may be adjusted by means of the screw 12 which is threaded into the block 9 and into the slide 10, as shown in Figs. 4 and 5. The roller 11 forms the second stationary support or stop for the bar or rod 13 to be bent in the machine.

As shown in Figs. 2 and 3, the disk 5 is provided at its periphery with a groove 14 into which is placed a rope 15, one end of said rope being secured to the disk at 16 as indicated in Fig. 3. The rope 15 runs over a pulley 17 journaled in a slide block 18 movable on a screw 19 and guided by guides 20 under the machine table. The screw 19 is journaled in the machine frame, as shown in Fig. 3, and may be turned by means of the handle 21, so that the slide block 18 and the pulley 17 may be moved in the direction of said screw 19 transversely to the machine. A scale 22 is secured to and moves with the slide block 18 below an opening 23, Fig. 4, in the machine table, so that the movement of the slide block 18 and the pulley 17 caused by rotation of the handle 21 may be controlled.

The other end of the rope 15 is secured to a crank pin 24 secured to a crank arm 25 on a shaft 26 to which rotary motion is imparted by means of a train of gears 27, 28, 29, 30, 31, 32, pulley 33 and belt 34 from a suitable motor 35.

The shaft 26 and crank arm 25 support a circular disk or plate 36 level with a bottom 37 in the machine frame for supporting the rope 15.

The vertical shaft 3 is also provided with a grooved disk 38 to which is secured one end of a rope 39 which is wound around said disk in the opposite direction to that of the rope 15 around the disk 14. The other end of said rope 39 is attached to a spring 40 secured to the machine frame.

In the operation of the machine the bar or rod 13 to be bent is introduced between the supports 4, 6 and 11 in such manner that

the end 4 of the shaft is on one side of the bar and the stud 6 and roller 11 on the other side of the bar. Assuming that the crank pin 24 is continuously driven by the motor 35 in the direction indicated by the arrow in Fig. 3, and is in the position shown in Fig. 3, it will pull the rope 15 along, the rope running over the pulley 17 and causing the disk 14 and the shaft 3 to rotate in the direction indicated by the arrows in Fig. 3 and Fig. 4. The stud 6 on the disk 14 will thus rotate in the same direction around the axis of the shaft 3, and the bar 13 being supported by the end 4 of the shaft and 10 against the roller 11 on the slide 10, said bar will thus be bent by the stud 6 around the end 4 of the shaft, as indicated in dotted and dashed lines in Fig. 4. This bending of the bar continues until the crank pin 24 15 has reached its position farthest away from the pulley 17, when the pull of the crank pin 24 on the rope 15 ceases, so that the disk 14 may rotate in the reverse direction actuated by the rope 39 and the spring 40. 20 Said reverse rotation of the disk 14 will be stopped by the stud 6 striking against one end of the slot 7 in the machine table 2, when the disk 14 and stud 6 are in idle position and the bar 13 may be removed and another bar inserted. A scale 41, Fig. 4, may be provided in the machine table for facilitating the proper insertion of the bar.

It will be understood that the angle of turning of the disk 14 is dependent upon 35 the operative length of the rope 15, or in other words upon whether the rope 15 is more or less stretched by means of the pulley 17, so that the crank pin 24 begins to exert a pull on the rope 15 at an earlier or 40 later stage after said pin has passed through its position nearest the pulley 17. The operative length of the rope 15 may be changed by adjustment of the pulley 17 by means of the handle 21 and screw 19, and the 45 adjustment may be read off on the scale 22 in the opening 23 in the machine table. By such adjustment it is thus possible to produce any desired bending of the bar or rod, and the adjustment may be effected while 50 the machine is in operation.

As shown in Figs. 1 and 5, the stationary support formed by the block 9, slide 10, and roller 11 is higher than at least one of the two other supports, the end 4 of the shaft 55 and the stud 6, in this case higher than both said supports, in order to prevent the bar 13, if it slides upward between the supports, from losing the engagement with the first named support, while it is still engaged 60 by the end 4 of the shaft and the stud 6, in which case the entire bar might be swung around the end 4 of the shaft.

Fig. 6 illustrates ordinary bends on reinforcement bars for concrete constructions,

and Fig. 7 illustrates a bend having a large 65 radius, which bend may be produced by means of the machine described above by adjusting the machine for only a very small angle of bending, and by feeding the bar forward a quite small distance after every 70 bending of the bar.

It will be understood that the invention is not limited to the embodiment above described and illustrated in the drawings, as various changes and modifications may be 75 made in the same within the scope of the invention as expressed in the claims.

I claim:

1. In a machine for bending metal bars and the like, the combination of two stationary supports for the bar, a third rotatable support for said bar, a rotatable disk supporting said third support, a rope secured to and wound around said disk, a rotary crank to which said rope is attached, 80 and driving means for said crank.

2. In a machine for bending metal bars and the like, the combination of two stationary supports for the bar, a third rotatable support for said bar, a rotatable disk 90 supporting said third support, a rope secured to and wound around said disk, a rotary crank to which said rope is attached, driving means for said crank, and means for adjusting the movement of said disk 95 caused by said crank and said rope.

3. In a machine for bending metal bars and the like, the combination of two stationary supports for the bar, a third rotatable support for said bar, a rotatable disk 100 supporting said third support, a rope secured to and wound around said disk, a rotary crank to which said rope is attached, driving means for said crank, and means for effecting a continuous adjustment of the 105 movement of said disk caused by said crank and said rope.

4. In a machine for bending metal bars and the like, the combination of two stationary supports for the bar, a third rotatable support for said bar, a rotatable disk 110 supporting said third support, a rope secured to and wound around said disk, a rotary crank to which said rope is attached, driving means for said crank, and means for 115 adjusting the operative length of said rope.

5. In a machine for bending metal bars and the like, the combination of two stationary supports for the bar, a third rotatable support for said bar, a rotatable disk 120 supporting said third support, a rope secured to and wound around said disk, a rotary crank to which said rope is attached, driving means for said crank, and a pulley for said rope adjustable so as to stretch said 125 rope more or less.
